UNITED STATES PATENT OFFICE.

HENRY W. GATLIN, OF KANSAS CITY, MISSOURI.

CURTAIN-STRETCHER.

1,264,175.

Specification of Letters Patent. Patented Apr. 30, 1918.

Application filed October 5, 1916. Serial No. 123,934.

To all whom it may concern:

Be it known that I, HENRY W. GATLIN, a citizen of the United States, residing at Kansas City, in the county of Jackson and 5 State of Missouri, have invented new and useful Improvements in Curtain-Stretchers, of which the following is a specification.

This invention relates to improvements in curtain stretchers and has for its chief characteristic to provide a device of this character having collapsible and movable stretching elements, the means for moving the elements being of novel construction to insure the thorough stretching of the curtains.

10 Another characteristic of this invention resides in the provision of a device of the above described character which may be readily collapsed to facilitate the storing or transporting of the same.

15 Another characteristic of this invention resides in the providing of a curtain stretcher which contains the desirable features of simplicity, durability and efficiency and furthermore a device which may be manufactured at a nominal cost.

Other objects of the invention will appear as the specification is read in connection with the accompanying drawings in which:—

20 Figure 1 is a top plan view of the device constructed in accordance with my invention;

Fig. 2 is a side elevation of the device;

Fig. 3 is an end elevation;

25 Fig. 4 is a perspective view of the structure in collapsed position.

Fig. 5 is a detailed view of the connection between the diverging rods of one of the adjusting means.

30 Fig. 6 is a detail side elevation illustrating the manner of connecting the side bars of the frame to one another.

Referring to the drawings in detail, my invention comprises a substantially rectangular frame which is composed of the side bars A and the end bars B, the under side of the end bars being provided with a co-extensive bracket 1 which is adapted to slidably receive the side bars A, thereby permitting the bars to be adjusted with relation to each other. The bars A and B are each provided upon their inner faces with the substantially L-shaped hooks 2, the hooks serving to detachably support the curtain 55 upon the frame as will be understood.

The side bars A are each formed of sec-

tions 3 and 4 which have their meeting ends hingedly connected to each other as at 5, the hinges being so arranged upon the sections as to permit the sections to be swung toward each other to allow the folding of the same. Each of the hinges 5 is mounted with 60 standing ears 6 while spanning the space between the side bars A and having the opposite ends thereof loosely mounted within the 65 ears 6 is a cross rod 7.

To adjust the end bars B toward or away from each other in stretching a curtain, I provide one of the end bars at its medial portion and upon the underside thereof with 70 a threaded annular collar 8 through which extends a threaded shank 9, the shank extending longitudinally of the frame and in parallel relation with the side bars A. The shank has its outer end formed with a 75 handle 10 to facilitate the manipulation thereof while its inner end terminates at a point adjacent the cross rod 7 and is formed with the head 11. The head has hingedly secured thereto one end of the rods 12, the 80 rods being arranged in diverging relation to each other and having their free ends secured to the inner face of the adjacent end bar B. The cross rod 7 is adapted to support the rods 12 of the shank 9 in horizontal 85 position but when the stretcher is collapsed, the cross rod may be removed to permit the collapsing of the rods 12 as will be understood. It will be evident from the foregoing description that upon rotating the shank 90 9 in the collar 8, the diverging rods 12 will be actuated to move the end bar or bars toward or away from each other to stretch the curtain as will be understood. Obviously, the manner of connecting the rods to 95 the head not only permits of the adjustment of the end bars in either direction, but further affords of the adjustment of the end bars toward or away from each other.

Certain of the end bars B are provided 100 upon their outer side faces with spaced guide members 13 in which are loosely mounted the threaded bars 14, the bars having one end thereof extending through threaded collars 15 formed on the side bars A. One 105 end of the bars 14 is provided with a handle 16 while the opposite or inner end is provided with an enlarged offset head 17, the head being adapted to engage the remaining side bar to permit the relative adjustment 110 of the side bar as will be understood. It will be manifest from the foregoing that the

side bars may be adjusted with relation to each other by means of rotating the threaded bars 14, the enlarged head 17 engaging the movable side bar as will be understood.

5 When it is desired to collapse the stretcher to facilitate the transporting of the same, it will be evident that by removing the cross rod 7 the sections 3 and 4 will then be free to be swung toward each other as shown in 10 Fig. 5 of the drawing. It will thus be seen that the frame assumes a compact form whereby the same may be readily transported or stored.

15 It is thought from the foregoing taken in connection with the accompanying drawings that the construction and operation of my device will be apparent to those skilled in the art, and that minor changes in size, shape, proportion and minor details of construction may be made, without departing 20 from the spirit and scope of the appended claims.

What I claim is:—

1. A curtain stretcher comprising side bars, end bars slidably receiving the side bars, the side bars being formed of foldable sections, hooks formed on each of the bars, means for effecting a relative adjustment of the bars, and supporting means for said adjusting means detachably engaging with the side bars.

2. A curtain stretcher comprising end bars and hinged side bars, brackets carried by the end bars and slidably receiving

the side bars, hooks formed on each of the 35 bars, a threaded rod carried by one of the end bars, rods hingedly connected to the threaded rod and to the remaining end bar, and means carried by one of the side bars for effecting an adjustment of the remaining 40 side bar.

3. A curtain stretcher comprising side bars of hinged sections, end bars, brackets carried by the end bars and slidably receiving the side bars, L-shaped hooks formed on 45 all of the bars, a cross rod detachably carried by said side bars, a threaded rod carried by one of the end bars, rods hingedly connected to the threaded rod and to the remaining end bar, said cross rod engaging 50 the threaded rod to support the same in horizontal position and rods threadedly mounted within one of the side bars and engageable with the remaining bar to effect a relative adjustment of the bars.

4. A curtain stretcher comprising end bars and hinged side bars, a threaded rod carried by one of the end bars, rods hingedly connected to the threaded rod and to the remaining end bar, means carried by one 60 of the side bars for effecting the adjustment of the remaining side bar, and means detachably engaging with the side bars for supporting the hingedly connected rods in a horizontal position.

65 In testimony whereof I affix my signature.

HENRY W. GATLIN.

Copies of this patent may be obtained for five cents each, by addressing the "Commissioner of Patents, Washington, D. C."
